(57) **CLAIM**

The ornamental design for a door outlet adaptor set, as shown and described.

DESCRIPTION

FIG. 1 is a front perspective view of a door outlet adaptor set shown separately without the cover in order to show details that would not be seen when assembled.

FIG. 2 is a front view thereof;

FIG. 3 is a rear view thereof;

FIG. 4 is a side view thereof;

FIG. 5 is a top view thereof;

FIG. 6 is a front perspective view of a door outlet adaptor set;

FIG. 7 is an exploded perspective view thereof;

FIG. 8 is an exploded side view thereof;

FIG. 9 is an exploded top view thereof;

FIG. 10 is an exploded bottom view thereof;

FIG. 11 is a front view of the front plate of the door outlet adaptor set shown separately without the cover and rear plate in order to show details that would not be seen when assembled;

FIG. 12 is a rear view thereof;

FIG. 13 is a front view of the rear plate of the door outlet adaptor set shown separately without the cover and front plate in order to show details that would not be seen when assembled; and,

FIG. 14 is a rear view thereof.

The broken lines in FIGS. 1-10 representing a door show the design as being used and form no part of the claimed design.

1 Claim, 11 Drawing Sheets
